UNITED STATES PATENT OFFICE.

THOMAS E. THOMPSON, OF CHICAGO, ILLINOIS.

AUTOMOBILE SIGNALING DEVICE.

Application filed May 29, 1925. Serial No. 33,767.

To all whom it may concern:

Be it known that I, THOMAS E. THOMPSON, a citizen of the United States, residing at 5508 Lexington Street, Chicago, in the 5 county of Cook and State of Illinois, have invented new and useful Improvements in Automobile Signaling Devices, of which the following is a specification.

This invention relates to an automobile 10 signaling device and has for its primary object the construction and association of various signaling devices into a very unique and compact apparatus.

An object of the invention is the novel 15 manner of associating the parts so that a single electric bulb is capable to provide all the illumination necessary for the various signaling elements.

With the above and other objects in view, 20 the invention will be better understood from the following description taken in connection with the accompanying drawings, in which:

Fig. 1 is a front elevation of the signaling 25 device with the display device in displaying position.

Fig. 2 is a similar view with the display device in its other position.

Fig. 3 is a vertical sectional view.

Fig. 4 is a perspective view of the display device.

Fig. 5 is a front elevation of another construction of my invention.

Fig. 6 is a side elevation.

Fig. 7 is a vertical sectional view through a portion thereof.

Again referring to the drawings illustrating two of the many constructions of my invention and more particularly to Figures 1, 40 2, 3 and 4, the numeral 1 designates a housing having an extension 2 provided with slots 3 for attachment to the housing of the automobile and further for supporting the usual license plate. Arranged within this 45 housing is a single bulb 4, light rays from which may pass through the open bottom 5 of the casing so as to illuminate the license plate. The housing is further provided with an opening 6 at the top for the purpose 50 hereinafter described.

This housing supports a red lens 7 for giving the permanent signal known as a tail light. Supported by the housing directly above the lens 7 is a plate 8 having letters 55 cut therein provided with any suitable word or group of words, to give proper informa-

tion to the driver of the following automobile. This plate 8 is normally closed by a shutter 9 pivoted to the housing as indicated at 10. Supported by the shutter is the 60 socket 11 for removably receiving the tongue 12 of the display device 13 which may be of any configuration or of any design to convey the proper meaning.

A spring 14 holds the shutter in closing 65 position and the cable 15 is used to operate the shutter having one end connected to the shutter and the other end to the foot pedal or any other element of the automobile. The construction shown in Figures 5, 6 and 7 is 70 practically identical with that just described with the exception that I include an additional opening 16 in the housing through which the light rays from the bulb may be passed rearwardly and this opening 16 is 75 normally closed by a second shutter 17 operated by a separate cable 18.

From the foregoing description taken in connection with the accompanying drawings, 80 it will be noted that the bulb 4 is capable of passing light rays through lens 7 and through plate 9 and further through the open bottom 5 for illuminating the license plate. Upon manipulation of the foot pedal, the shutter 9 is thrown to a position to uncover 85 plate 8 and simultaneously move the display device 13 to displaying position. When in such displaying position light rays from the bulb 14 will illuminate the displaying device. 90

Quite often it is an advantage in backing to illuminate behind the automobile and this can be accomplished by pulling cable 18 and pulling shutter 17 to position to uncover 95 opening 16.

It is, of course, to be understood that the design of the various parts and manner of associating the same may be changed in various ways and therefore I do not desire to be limited in any manner except by the 100 claims hereunto appended.

Having thus described my invention, what I claim is:

1. In combination a casing supporting a display plate and provided with an opening, a bulb within the housing, a shutter for covering and uncovering said plate, means for giving such movement to said shutter and a signal element associated with said shutter so that when the shutter is in position to uncover said plate, said signal element will be in displaying position and re- 105 110 115

ceiving light rays from the bulb through said opening.

2. An automobile signaling device comprising a housing having an extension provided with slots and an opening at the top, a red lens supported by the housing, a display plate carried by the housing above said lens, a shutter for covering and uncovering said plate and pivoted to said housing, a socket carried by said shutter, a display element removably supported by said socket and a foot pedal control cable connected to said shutter.

3. An automobile signaling device com-

prising a housing having an extension provided with slots and an opening at the top, 15 a red lens supported by the housing, a display plate carried by the housing above said lens, a shutter for covering and uncovering said plate and pivoted to said housing, a 20 socket carried by said shutter, a display element removably supported by said socket and a foot pedal control cable connected to said shutter and a second shutter for covering and uncovering a second opening in said 25 housing.

In testimony whereof I affix my signature.

THOMAS E. THOMPSON.
